Primary Examiner — Natasha Vujcic*Assistant Examiner* — Gilbert B Ford(57) **CLAIM**

The ornamental design for a femoral venous catheter, as shown and described.

DESCRIPTION

FIG. 1 is a top front right perspective view of a femoral venous catheter showing my new design;

FIG. 2 is a top front left perspective view thereof;

FIG. 3 is a bottom rear left perspective view thereof;

FIG. 4 is a bottom rear right perspective view thereof;

FIG. 5 is an enlarged front elevation view thereof;

FIG. 6 is an enlarged rear elevation view thereof;

FIG. 7 is a top plan view thereof;

FIG. 8 is a bottom plan view thereof;

FIG. 9 is a right-side elevational view thereof;

FIG. 10 is a left-side elevational view thereof;

FIG. 11 is an enlarged view of a portion of the femoral venous catheter shown in FIG. 2; and,

FIG. 12 is an enlarged view of a portion of the femoral venous catheter shown in FIG. 4.

The dash-dash broken lines represent boundaries of the enlarged portion and forms no part of the claimed design.

1 Claim, 12 Drawing Sheets(56)
